UNITED STATES PATENT OFFICE.

HARRISON H. SOUTHWORTH, OF CLEVELAND, OHIO, ASSIGNOR, BY MESNE ASSIGNMENTS, TO THE ICELESS MACHINE COMPANY, OF CLEVELAND, OHIO, A CORPORATION OF OHIO.

FUEL-GAS BURNER.

Patented Nov. 30, 1915.

1,162,315.

Specification of Letters Patent.

Application filed May 8, 1914. Serial No. 837,117.

To all whom it may concern:

Be it known that I, HARRISON H. SOUTHWORTH, a citizen of the United States, residing at Cleveland, in the county of Cuyahoga and State of Ohio, have invented a certain new and useful Improvement in Fuel-Gas Burners, of which the following is a full, clear, and exact description, reference being had to the accompanying drawings.

- 10 This invention relates to improvements in burners, and one of the main objects of the invention is to provide a burner applicable for connection with devices in which, during certain periods of the operation of said devices, cooling or other liquid is caused to flow over or about the burner and is apt to drip upon the same and stop up the orifices thereof. An example of such a device is an absorption refrigerating apparatus 15 wherein a still is alternately heated by the burner and cooled by cooling liquid. In such cases with burners heretofore used, after the liquid is turned off and the gas is again turned on, the small orifices of the burner, if made small enough to prevent back firing, are frequently plugged by the liquid and fail to permit the escape of the gas and thus greatly interfere with the efficiency of the burner.
- 20 One of the objects of my invention is to overcome this difficulty.
- Another feature of my invention consists of an improved pilot light attachment connected with the burner whereby the pilot is removed at some distance from the burner, so as not to be extinguished by the liquid, falling on or about the burner, or the resulting hot vapor, and so arranged that when the gas is turned on flame is projected from 25 the pilot light to the burner itself, thus bridging this space and lighting the burner. This attachment possesses other advantages which appear more clearly in the following specification.
- 30 In the drawings Figure 1 is a view representing a vertical section through a refrigerating apparatus provided with a still which is alternately heated by means of my improved burner and cooled by water; Fig. 35 2 is a plan view of the burner as applied to refrigerating apparatus as shown in Fig. 1, looked at as viewed from above a plane indicated by the line 2-2 of Fig. 1; Fig. 3 is a view representing on an enlarged scale a 40 partial longitudinal sectional view of the

burner in a plane indicated by the line 3-3 of Fig. 2; Fig. 4 is a transverse section through the burner in a plane indicated by the line 4-4 of Fig. 3; Fig. 5 is a detailed sectional view on an enlarged scale of a valve fitting used in my apparatus, the plane of the section being indicated by the line 5-5 of Fig. 1; Fig. 6 is a partial vertical section on an enlarged scale of the burner and pilot light attachment, the plane of the section being indicated by the line 6-6 of Fig. 2; Fig. 7 is a view representing a vertical section through Fig. 6 in a plane indicated by the line 7-7 thereof; Fig. 8 is a top plan view showing a modified form of my burner and pilot light; Fig. 9 is a side elevation of the modification shown in Fig. 8; Fig. 10 is a sectional view through the same, taken in a plane indicated by the line 10-10 of Fig. 8.

Referring now to the embodiments of my invention illustrated in the drawings, 11 indicates a still in a refrigerating apparatus which alternately acts as a generator and as an absorber and which during the period of generation is heated from below by a burner and during the period of absorption is cooled by means of cooling water.

The refrigerating apparatus shown in the drawings is of that type described in an application executed of even date herewith and filed on the 8th day of May, 1914, Serial No. 837,118. 12 indicates the condenser in said apparatus and 13 a water tank in which said condenser is located.

14 indicates a cooling water pipe extending longitudinally above the still and connected with the tank 13 in such manner as to discharge water supplied from said tank upon the still during the period that said still is acting as an absorber.

15 indicates my improved burner which extends longitudinally below the still and is adapted to heat the same during the period when said still is acting as a generator. The water after passing from the discharge pipe 14 flows about the body of the still and drops from thence into a tank 16 which overflows into a sewer connection. Manifestly the water will fall upon the burner and will enter the openings therein to a certain extent.

Automatic means for controlling the supply of cooling water to the discharge pipe 14 and for controlling the supply of gas to the burner are provided, but as these and

the other features of the refrigerating apparatus as such, form no part of the present invention and are fully described in the application above referred to, further reference thereto in the present specification is not necessary.

The burner 15 consists of a pipe 17 extending the full length of the still or other device to be heated connected at its ends by suitable elbow fittings 18 to upright pipes 19. Said pipes 19 are open at the bottom and are connected by flanged fittings 20 to brackets 21 by means of which they are supported as shown from bars 22 extending across and attached to the side walls of the tank 16. The pipes 19 extend downwardly a sufficient distance so that their lower ends will be sealed by means of the water contained in the tank in which the water stands, as shown in the drawings, at a level indicated by the dot and dash line 23. This construction provides a burner pipe sealed at both ends and at the same time one from which water, flowing into it, is readily discharged, running out at each end of the pipe 17 and down through the pipe 19 into the water contained in the tank. The water in the tank is of course maintained at a substantially constant level by means of an overflow outlet pipe 24.

There are placed at longitudinally spaced intervals in the pipe 17, a plurality of upright discharge nipples 25 by means of which the combustible mixture is discharged from the burner. Said nipples consist of short tubes secured in suitable apertures or openings in the top of the pipe 17. As shown, and as a preferred construction, the alternate nipples are placed at opposite angles to a vertical plane, as clearly illustrated in Fig. 4, in order to spread the flame over a larger area of the part (in this case the still) that is to be heated. This also provides better secondary air mixture for the flame.

In order to obtain the best efficiency of the combustible mixture escaping through the burner openings formed by the bore of the nipples 25, in the burner, it is desirable to have these openings very small. Water, however, tends to remain in these nipples by capillary action and if the nipples are cut off straight across their lower end, the drop will adhere to the lower end of the nipple, thereby plugging the same and preventing the escapement of gas therethrough. To prevent this, I provide a point at the lower end of the nipples formed by beveling them at a sharp angle, as shown at 26, which causes the water to flow off from the lower end of the nipples instead of being retained thereby. This allows water which gets into the nipples to be drawn at once into the burner pipe 17, through which it may flow into the pipes 19 and tank 16, as described.

Accordingly, no matter how much water may drop from the still onto the burner after the supply of water flowing over the still has been shut off, the nipples will all be clear and open for the passage of gas.

The burner pipe has connected to it two longitudinally spaced branch pipes 27, 27, (as shown in Fig. 2) which are each connected by a suitable air mixing device 28 with a pipe 29 in which is interposed a three-way fitting 30 connected to the main gas supply pipe 31 (see Figs. 1, 2 and 5). The supply of gas to the three-way fitting is controlled by suitable valves which in the apparatus referred to are controlled automatically.

32 indicates a pipe connected with the third way in the fitting 30 and acting to supply gas to the pilot light 33. This supply may be regulated by a threaded needle 32^a adapted to close the passage leading to the pipe 32. The pilot light 33 consists of a casing 34 having a closed end 35, a top wall 36 and side walls 37, 37 and being open at the bottom and at its opposite end. The side walls 37 are attached by means of suitable ears 38, 38, to the burner pipe 17 in such manner that the open end of the casing is open up to a plane slightly above the level of the burner nipples 25.

39 indicates a burner tube fixed in the closed end 35 of the casing 34 and extending longitudinally through said casing to a point near its open end adjacent to the plane of the nipples 25. The pipe 32 is secured in the end of the said burner tube. The burner tube is preferably provided at its outer inlet end with air openings 40 and may have a plurality of longitudinally spaced openings 41 in its top side. The discharge end of the burner tube is pinched, as indicated in Fig. 6, to contract the outer opening and thus retard the flow of gas therethrough. As shown, the casing 34 has a lateral extension 42 in which is formed a passage 43 connected by a pipe 44 with a source of fuel gas supply such that it will have a constant supply of gas and with upright passages 45, 45 opening through the top of the casing and provided with burner tips 46, 46.

47 indicates a stack placed on top of the casing 34 and inclosing the burner tips 46. Said stack has a hinged or movable cover 48 for convenience in lighting the gas at the burner tips 46 and also has ventilation openings 49 to supply air to said burner tips. A passage 50 connects the interior of the casing 34 with the space within the stack 47 and opens one or more of the burner openings 41 in the burner tube 39 to the influence of the burning gas at the tips 46.

The operation of the pilot light is as follows: The gas is constantly burning at the burner tips 46. When the gas is turned into

the three-way fitting 30 it flows through the pipes 29, the air mixing devices 28, 28, and the branch pipes 27, 27 to the main burner pipe 17 whence it escapes as a combustible mixture through the burner nipples 25. At the same time gas flows through the pipe 32 into the burner tube 39 of the pilot light, drawing in with it a supply of air through the openings 40. This mixture of air and gas escapes through the burner openings 41 and through the contracted end of the burner tube 39 and some of it entering through the passage 50 into the neighborhood of the nipples 46 is ignited. The flame thus started flashes along the length of the burner tube lighting the gas escaping through the successive openings 41 until it is finally communicated to the gas escaping through the contracted end of the burner tube whence the flame is projected to the combustible mixture escaping from the nipples of the main burner, igniting the same.

In Figs. 8 to 10 inclusive, I have shown a modification of the burner more particularly intended for use in cases where the main burner tube is short and the pilot light may be located conveniently at the end thereof instead of at a point midway of the ends as in the case just described. In this case 17^a indicates the burner pipe, 18^a, 19^b, the fittings at the end thereof and, 19^a, 19^a the upright pipes which are intended to be sealed by water as before. The nipples 25^a in this case are shown as all located in a vertical plane instead of inclined alternately on opposite sides of said plane as in the prior described construction. 34^a indicates a casing inclosing the burner tube 39^a as above described and 46^a indicates the burner tube nipples intended to be constantly burning. All of the like parts are indicated by like numerals with the superscript "a". The burner tube 39^a in this case, however, instead of providing its own mixture of air with the gas is arranged to take off a supply of mixed gas and air from the same source which supplies said mixture to the main burner pipe 17^a. The T-fitting 19^b which provides the connection between the pipe 17^a and one of the upright pipes 19^a has one end connected to a mixing valve. The tube 39^a has a branch 52 which is attached to and opens laterally into the T-fitting 19^b. Said branch has an end part 53 which extends across the path of the gas entering the T-shaped fitting 19^b, the tube being closed at the end but being provided with a lateral opening 54 which is adapted to take up some of the mixture as the gas proceeds on its path toward the main burner. The operation in this case is exactly the same as in the case first described.

From the foregoing description it will be seen that I have provided a burner over which water may flow without stopping up

the orifices thereof and which is particularly adapted for use with devices in which a member is adapted to be alternately heated by the burner and cooled by cooling water flowing over the same, the burner being sealed at each end by the water in a tank or other receptacle beneath the burner and into which the water flowing through the orifices of the burner is adapted to drain, and also that I have provided a burner having its orifices formed by nipples which cannot retain water by capillary action but from the lower ends of which the water will drip freely without stopping up or plugging the same.

Having thus described my invention, what I claim is:

1. In a burner, the combination of a tube having an inlet passage and a series of nipples projecting through the wall of the tube, said nipples being arranged in a plurality of rows oppositely inclined, the adjacent nipples in the adjacent rows being out of transverse alinement.

2. A burner comprising a casing and a series of small tubes extending through the wall thereof and having a bore no larger in diameter than that of a drop of water, the inner end of such small tubes having their openings elongated to prevent the tube being sealed by such drop.

3. In a burner, the combination of a casing, a series of tubes extending into the casing and forming the outlet orifices of the burner, said tubes having an elongated opening formed at their inner ends to prevent water forming a globule extending across the bore of the tube.

4. In a burner, the combination of a casing, a series of nipples mounted in said casing forming the outlet orifices thereof, said nipples having their lower ends beveled to prevent a globule of water forming across the bore of the nipples thereby preventing the escape of gas therefrom.

5. The combination of a gas burner, means for directing water over it; a downwardly opening port in said burner, and means for retaining water beneath said burner so that its surface will come above the port and seal the same.

6. The combination with a burner, of a member adapted to be alternately heated thereby and cooled by water, said burner having orifices comprising passages the inside openings of which are vertically elongated to prevent water forming in globules closing the same, and said burner having a downwardly extending passage with an opening below the burner, a receptacle beneath the burner adapted to retain water at a height sufficient to close said last named opening.

7. In a burner, the combination of a casing having a series of upwardly facing

openings in its upper surface, whereby water may drop into the casing, a draining pipe depending from the casing, and a vessel adapted to contain liquid over the lower end

5 of the draining pipe.

8. In a burner, the combination of a horizontal tube having discharge openings, an elbow at the end of the tube communicating therewith, an upright pipe communicating with the elbow and having an opening below said elbow, a support connected to the upright pipe, and means for maintaining liquid above said opening of said upright

10 pipe.

9. In a burner, the combination of a casing having upward discharge openings, a tubular standard supporting the casing and communicating with its interior, a water seal over the lower end of the tubular standard, and a passageway for admitting gas to the interior of the burner.

15 In testimony whereof, I hereunto affix my signature in the presence of two witnesses.

HARRISON H. SOUTHWORTH.
